(57) **CLAIM**

The ornamental design for a sensor with connector, as shown and described.

DESCRIPTION

FIG. 1 is a top rear perspective view of a sensor with connector according to the claimed design.

FIG. 2 is a front view of the sensor with connector.

FIG. 3 is a rear view of the sensor with connector.

FIG. 4 is a right side view of the sensor with connector.

FIG. 5 is a left side view of the sensor with connector.

FIG. 6 is a top view of the sensor with connector.

FIG. 7 is a bottom view of the sensor with connector.

FIG. 8 is a perspective view of the sensor with connector with the sensor and connector in a detached configuration.

FIG. 9 is a front view of the sensor in the detached configuration of FIG. 8.

FIG. 10 is a rear view of the sensor in the detached configuration of FIG. 8.

FIG. 11 is a right side view of the sensor in the detached configuration of FIG. 8.

FIG. 12 is a left side view of the sensor in the detached configuration of FIG. 8.

FIG. 13 is a top view of the sensor in the detached configuration of FIG. 8; and,

FIG. 14 is a bottom view of the sensor in the detached configuration of FIG. 8.

The broken lines in the drawings illustrate portions of the sensor with connector that form no part of the claimed design.
